UNITED STATES PATENT OFFICE.

LYTLE J. HUNTER, OF COVINGTON, KENTUCKY, AND HARRY C. HUNTER,
OF WINTON PLACE, OHIO.

TICKET-CONTROLLING MACHINE.

SPECIFICATION forming part of Letters Patent No. 510,428, dated December 12, 1893.

Application filed February 25, 1893. Serial No. 463,742. (No model.)

To all whom it may concern:

Be it known that we, LYTLE J. HUNTER, residing at Covington, in the county of Kenton and State of Kentucky, and HARRY C. HUNTER, residing at Winton Place, in the county of Hamilton and State of Ohio, have invented certain new and useful Improvements in Ticket-Controlling Machines, of which the following is a specification, reference being had therein to the accompanying drawings.

This invention relates to ticket controllers, or machines from which tickets or similar tokens may be ejected, and canceled or not canceled, as desired by the operator.

The objects of the invention are to produce a machine or instrument, which can be carried on the person of a street car conductor or other operator, in which a strip of tickets may be stored, and to enable the person controlling the device to issue the tickets therefrom in a mutilated or unmutilated state; also to provide a punch or mutilating attachment by which the ticket may be canceled after its issue from the machine, or a separate ticket canceled; also to improve the construction of parts, and combination of various parts of a machine of the character described.

Figure 1 is a perspective view of a machine of the character described, showing part of the suspending belt or strap, and showing a ticket projecting from the machine. Fig. 2 is a vertical section partly in elevation on a plane parallel with the casing, and bisecting the handle (line $x x$, Fig. 3). Fig. 3 is a front elevation, with the casing removed, and parts broken away. Fig. 4 is a section or elevation, from the reverse side of Fig. 2, taken inside the casing, and with the partition removed to show the operating parts (line $y y$, Fig. 3). Fig. 5 is a cross section on line $z z$, Fig. 4. Fig. 6 is a cross section on line a, a , Fig. 4. Fig. 7 is a detail of the feed roll driving mechanism and some connections detached. Fig. 8 is a detail of locking pawl. Fig. 9 shows details of feed roll gear. Fig. 10 is a perspective detail of principal operating parts.

The intention of the device is that a ticket be issued to every passenger or person who pays a fare. If the ticket be punched or canceled it has no further value, except possibly a slight arbitrary value for redemption. If

the ticket be not punched or canceled it may be used as a transfer. A ticket may be twice punched, to denote that it is a half fare ticket. In fact the uses to which the device may be applied are numerous. The construction and operation of the device are described herein.

The casing A is preferably of sheet metal, and contains a suitable frame work B which supports the operative parts. A thin plate or partition, C, separates the body of the casing into two chambers, one of which chambers contains most of the operating parts, the other chamber being a receptacle for a roll of tickets, which roll is indicated at D, Fig. 4. The paper constituting the roll or coil of tickets is printed in a long slip, and the length of each ticket is equal to the circumference of the feed wheel, or to the feed of said wheel at each reciprocation of the handle. The tickets in the strip are consecutively numbered, so that if a record be kept of the number of tickets in the machine in the morning, when the machine is returned at night a glance at the outer ticket on the roll will enable the inspector to determine how many tickets have been used during the day. The roll of paper is placed loosely in the proper chamber, no spool or reel being needed to support it, and the tickets are fed out by the action of the machine, as will be explained. The outer end or the first ticket of the reel, (which may be either the highest or lowest consecutive number) is preferably passed through the guide clamp, which consists of a smooth cylinder or rest 1, and the bearing plate 2, which is held down upon the paper by the spring 3, thus forming a spring friction device which permits the paper to be drawn forward, merely holding the slip taut, but prevents it from being pushed back toward the roll or reel. The guide clamp is shown directly over the paper roll chamber. After passing the guide clamp, the strip of paper passes over the roughened feed roll 5, and between said roll and the elastic or slightly yielding bearing roll 6. The strip of paper is nipped between these rolls so tightly that it is compelled to partake of the movement of the feed roll. Both rolls are supported in suitable bearings in the frame, in front of the guide clamp. After passing over

the feed roll the paper slip passes between guide plates 7 and 8, and out of a slot in the front of the casing. Preferably one of the plates is of steel, with a notched or saw-tooth 5 edge, and projects slightly in front of the casing, through the slot therein, forming a cutting edge against which the ticket may be torn off, when projected from the casing.

By the reciprocation of the handle, the feed 10 roll 5 is caused to revolve intermittently, in one direction only, and so feed forward the paper strip just the length of a ticket at each operation of the handle. The mechanism by which this is effected will now be described.

15 The handle 10 projects below the casing, and is attached to rod 11, which is guided in ways in the casing, so that it may be drawn down by a pull on the handle. The rod 11 passes through bearings 13 and 14 on a slide 20 bar 12, and has shoulders above and below said bearings, or is otherwise so connected that rod 11 may rock in said bearings, but any longitudinal movement of the rod causes the slide bar to move with it. The slide bar 25 is guided by brackets 17 and 18, and by a pin 19 in the casing extending into a slot 20 in the draw bar, so that said bar may reciprocate vertically in the casing.

The draw bar 12 has a pin 22, extending 30 from one side thereof. This pin enters a slot 23 in one arm of a sector 25. This sector 25 has gear teeth on its arc or periphery, and its hub 27 is supported on a fixed pivot or pintle 26 in the casing. A strong coiled spring 27 35 surrounds the hub and is connected thereto or to the sector at one end, and the other end of the spring is attached to a stud 29 in the casing. The tendency of this spring is to work the sector to the position shown in Fig. 40 2. By a downward pull on the handle 10 the bar 12 is drawn down, and the pin 22 extending into slot 23 causes the sector plate to work on its pintle, against the force of spring 27. The gear 35, at the periphery of the sector, engages a pinion 40 which is mounted on the shaft 45 of the feed roll 5. The pinion has a one toothed ratchet wheel 41 rigidly connected thereto. For convenience, this ratchet wheel is practically inclosed in a recess in the end of the feed 50 roll 5, and a pawl 39, which is attached by its pivot to feed roll 5, is pressed against the periphery of the ratchet wheel by spring 38. When the pinion 40 is rotated by the action of the gear on the sector, the single tooth on the 55 ratchet 41 engages pawl 39, and causes the feed roll to rotate. There is a notch 31 in the periphery of the feed roll 5. A pawl 32 is hung on a pintle or stud in the frame, and is pressed toward the roll by spring 33, so as to engage 60 the notch 31 whenever the parts are in position for such engagement. The pawl 32 has an arm or lever 34, which is in the path of movement of a pin 36, which pin projects from the side of the sector plate. By these 65 connections, whenever the sector plate is rocked, it causes pinion 40 to rotate. The pinion 40 and ratchet 41 being rigid, ratchet 41

will turn in one direction, pawl 39 riding on the face of the wheel, and roll 5 will not be moved, being held by pawl 32; and this takes 70 place when handle 10 is drawn down; but at the very completion of the downward movement of the handle and rocking of the sector, the pin 36 in the sector engages the lever 34 which is rigid with pawl 32, and so disengages pawl 32 from the notch in the feed roll. Then if handle 10 be released, the sector is rocked upward by spring 27, and the pinion 40, rotating in reverse direction, will by means of its ratchet and pawl engagement 80 cause the feed wheel to rotate with it. The backward movement of the sector releases pawl 32, which falls again into the notch in feed roll 5 when said roll has made a complete revolution. 85

The movement of sector 25 under the influence of a downward pull of handle 10 does not affect the feed roll 5 at all unless the sector be rocked far enough to disengage pawl 32 from its notch in the feed roll. When it 90 has moved so far, the reverse movement of the sector is enough to revolve the feed roll one revolution, and having made that revolution the pawl 32 will stop it. Such revolution of the feed roll advances the paper strip 95 just the length of one ticket. Consequently a movement of the handle less than a complete reciprocation will have no effect at all in feeding out tickets; while if the handle be drawn down to the extent of its movement, 100 the release of said handle will permit the spring 27 to return the parts to normal position, and a ticket will be fed out by the action of the parts described.

The bar 12 has an arm 42; a pin 43 on this 105 arm, extends through a slot in lever 44, which lever is pivoted to the casing or frame, as at 45. One arm of this lever 44 extends through a mortise in punch 49. This punch 49 projects up, and moves in a hole 48 in jaws 46 110 and 47, outside the casing. A very slight downward movement of handle 10 and bar 12 causes lever 44 to rock, and actuate punch 49, so that it will punch a hole in a ticket which may be entered between jaws 46 and 115 47. Thus to operate punch 49 it is not necessary to draw down the handle far enough to operate the feed roll 5. The jaws 46 and 47 are curved, to guide a ticket to the punch.

There is a punch, 65, close to the guide 120 plates 8 and 7 and operating through a passage in said plates. This punch may be actuated to punch a hole in the ticket which is between the feed rolls and resting on the guide plates or shelves. The mechanism by 125 which this punch is worked will now be described.

The rod 11 has a head 60 projecting at one side thereof. This head may be rocked, by a slight turn of the rod in its bearings 13 and 14, so as to move down without engaging the punch actuating mechanism; but a normal pull, straight down on handle 10, carries head 60 against a fly 61, pivoted to lever 62, which

lever is pivoted to the frame or casing. The fly 61 is held by a spring 63, and forms a rigid extension of lever 62 as against downward pressure, but will yield to permit head 60 to pass by the lever 62 in moving upward, this being a common mechanical connection. One arm of lever 62 passes through a mortise in punch 65. Punch 65 is guided in bearings 66 and 67 in the frame or casing. A coil spring 69 surrounds the shank of the punch, and is attached to one of the bearings and the punch shank, tending to draw the punch back from operative position. When handle 10 is pulled directly down, the head 60 strikes fly 61, and carries down the fly and that end of lever 62, thus lifting the other end of lever 62 and forcing the punch upward, causing it to perforate any ticket which may be between the guide shelves or plates 7 and 8. The downward movement of head 60 swings lever 62 on its fulcrum, until head 62 rides past the end of the lever and fly. This permits spring 69 to draw the punch back instantly, retracting it from the ticket which lies between the guide plates 7 and 8. This happens before the handle reaches the end of its downward movement. The completion of the downward movement causes the mechanism heretofore described to actuate the feed roll, and project this ticket, so perforated or canceled, from the casing, where it may be torn off from the slip. If, however, it is desired to project a ticket which has not been punched or canceled, the rod 11 is slightly rotated in bearings 13, 14, against the pressure of spring 71, which tends to hold the head 60 in position to engage the fly 61. When so turned (by a slight twist on handle 10) the head 60 is out of line with fly 61, and may then move past the fly and lever 62 without moving said lever or the punch 65. Then if the handle be drawn fully down the feed roll will be actuated, and a ticket projected without having been punched or mutilated. In returning to normal position, the handle 10 may be released, and whatever the position of head 60 it will not actuate lever 62 in rising, as fly 61 will yield and allow the head to pass. Head 60 is shown as inclined on one side to easily effect this passage.

The draw bar 12 has an abutment 75 which is in position to engage a fly 76 on the end of bell crank lever 77. This fly is held toward the lever by spring 78, and the lever is pressed by spring 79. When the abutment 75 engages fly 76 it rocks the bell crank lever 77. As soon as the abutment rides past the fly, spring 78 throws the lever 77 back, so that clapper 80 is brought smartly against bell 81. Clapper 80 extends through a hole in the casing. Bell 81 is preferably protected by a dome 82 outside the casing proper.

The punches have passages to deliver the wads or slips cut from the tickets outside the casing.

Fixed jaws 46, 47, are curved upward and outwardly to guide the ticket.

The partition C is turned over at top into a flange 90, which acts as a detent to prevent the roll of tickets from catching or kinking. 70 One side of the casing opens to admit the roll of tickets, and the leading ticket is fed through the friction device and to the feed roll, and when properly entered each succeeding ticket will follow the first. 75

The roll 5 may be roughened at its central part only, and the rubber roll 6 opposite this central part will hold the ticket slip close to the feed roll, so that it shall feed forward steadily. 80

It will be understood that changes may be made in many details without departing from the spirit of our invention. The broad ideas are that the feed wheel shall act in one direction only, and on the return stroke of the 85 handle, so that a ticket cannot be fed part way out, and less than a full movement of the handle shall not move the ticket at all, although the punches may move without moving the tickets. We also have special advantages in the arrangement by which the roll of tickets is held without any reel or support other than a mere receptacle. 90

We claim—

1. In a machine of the character described, 95 the casing having a chamber for the roll of tickets, the guide clamp consisting of a bar and a spring pressed plate in proximity thereto, between which the ticket passes, the feed rolls, and guide - plates between which the 100 ticket is projected from the casing, substantially as described.

2. In a machine of the character described, the combination with the inclosing casing, of the feed rolls, the guide plates in proximity 105 thereto between which the ticket passes, the guide clamp and a punch in position to perforate the ticket while it is between said plates and before it is projected from the casing. 110

3. In a machine of the character described, the combination with the casing of the feed roll supported therein, the feed clamp the reciprocating handle, and gearing connected to the handle and operating on the feed roll to 115 actuate said roll in one direction only, substantially as described.

4. In a machine of the character described, the combination with the casing or frame, of the reciprocating handle, the geared sector 120 supported in the frame and connected to the handle, and the feed roll having a pinion in engagement with said sector gear, substantially as described.

5. In a machine of the character described, 125 the reciprocating handle and its connected gear, the feed wheel and an intermediate gear, actuated by the gear connected to the handle, and engaging the feed roll to actuate the same in one direction only, substantially as 130 described.

6. In a machine of the character described, the handle and its connected gear, the feed roll and gearing connecting to said actuating

gear, and a locking pawl engaging the feed roll and disengaged only by the mechanism at the extreme movement of the handle, in combination substantially as described.

5 7. In a machine of the character described, the combination with the feed roll and actuating mechanism therefor engaging said roll to move it in one direction only, of a locking pawl engaging said roll to hold it until unlocked by the extreme movement of the roll driving gear, substantially as described.

15 8. The combination of the casing having a roll or slip of tickets therein, of the operating handle, the feed roll, and intermediate gear connected to the handle and feed roll to operate only on the return of the handle after making a complete stroke, and paper guiding clamps by which the strip of paper is directed to the feed roll, substantially as described.

25 9. In a machine of the general character described the reciprocating handle, the operating gears connected thereto, and the feed roll having a ratchet wheel with a single tooth at a position corresponding to the movement of the feed roll periphery to deliver a ticket, and a pawl engaging said tooth to rotate the roll on the return movement of the handle, all combined substantially as described.

30 10. In a machine of the general character described the combination of the reciprocating handle, the oscillating sector plate connected thereto and having gears thereon, the pinion in engagement with said sector plate, and the feed roll having ratchet and pawl connection to said pinion, all combined substantially as described.

40 11. In a machine of the general character described the feed roll, the pinion on the same shaft therewith, the single tooth ratchet and pawl connection by which said roll is driven from the pinion, the roll locking pawl, and driving gear connected to the handle and operating on the pinion to actuate the same and on the roll-locking pawl to release the roll at the proper time, all combined substantially as described.

45 12. In a machine of the general character described the operating handle and geared sector connected thereto, the spring acting on the geared sector, the pinion, feed roll, and a rack and pawl connection between the same, and a roll locking pawl engaging the feed roll, all combined and relatively arranged substantially as described.

55 13. In a machine of the general character described the reciprocating handle and slide bar connected thereto, the rocking sector and spring operating to move the same in one direction, the slot and pin connection between the slide bar and sector, and the feed roll having geared connection to the rocking sector, all substantially as described.

60 14. The reciprocating handle and geared connections operating on the feed roll to operate the same in one direction only, at the return stroke of the handle, and the supple-

mentary punch connected to the handle and actuated by the first movement thereof, relatively arranged in a ticket controlling machine, substantially as described. 70

15 15. In a machine of the general character described the reciprocating handle and the punch operating externally of the casing and connected indirectly to the handle, and the 75 curved guiding jaws outside the casing having a slot between them through which the punch acts, all substantially as described.

16. In a machine of the general character described the combination with the reciprocating handle, of a punch, a spring acting on said handle to retract the same, and a lever acting on the punch, and having a contact engagement with a projection from the handle in passing, whereby the punch is actuated by 85 the movement of the handle, and immediately retracted, substantially as described.

17. In a machine substantially as described, the reciprocating handle, a punch connected to the handle through intermediate mechanism, whereby it is operated by the first movement of the handle in one direction, the feed roll and an actuating gear operatively engaging the same in one direction only, and means connected to the handle by which said gear 95 is actuated only on the second or return movement of the handle.

18. In a machine substantially as described, the reciprocating handle, the spring-pressed punch, and the lever intermediate the punch 100 and the handle and in position to engage both, and a loose fly forming the engaging abutment, whereby the movement of the handle is operative on the punch in one direction only, substantially as described. 105

19. In a machine of the character described, the combination of the reciprocating handle and rod having an operating head, the spring retracted punch, and an intermediate lever having a fly in position to engage the handle 110 head, and the feed roll and intermediate gears actuating the roll from the handle on the return movement thereof, substantially as described. 115

20. In a machine of the character described, 115 the combination of the reciprocating handle hung in a draw bar and having a rocking movement therein, the punch and its lever in position to be engaged by a projection from said handle when moving in normal direction 120 only, and the feed roll and its operating gear connected to the handle bar to operate only on the return movement of said handle bar, substantially as described.

21. In a machine of the general character described the combination with the handle and draw bar, of the punch and intermediate lever connections operating the punch on the forward movement of the handle, the feed roll and intermediate gear connections operating on the return movement of the handle, and the alarm operated at the completion of the forward handle movement, substantially as described. 125 130

22. In a machine of the general character described the combination with the casing, guide clamp, and feed rolls therein, of the partition having its edge turned over the chambers for the ticket roll, and interposed between said roll and the guide clamp, all substantially as described.

In testimony whereof we affix our signatures in presence of two witnesses.
